PERCIVAL FAULKNER KING, OF VANCOUVER, BRITISH COLUMBIA, CANADA.

UMBRELLA.

1,313,899.

Specification of Letters Patent. Patented Aug. 26, 1919.

Application filed July 12, 1918. Serial No. 244,598.

To all whom it may concern:

Be it known that I, PERCIVAL FAULKNER KING, a subject of the King of Great Britain, and a resident of the city of Vancouver, in the Province of British Columbia, Canada, have invented certain new and useful Improvements in Umbrellas, of which the following is a specification.

My invention relates to improvements in umbrellas, and the object of my invention is to devise an umbrella capable of being disassembled by the user as to all its parts so that it may be readily folded up into small bulk and as readily assembled again, thereby providing an umbrella which is of great convenience and utility. A further object is to provide an umbrella from the construction of which wiring is entirely eliminated.

I attain these objects by the construction illustrated in the accompanying drawings in which—

Figure 1 is a view showing the umbrella pole and one rib.

Fig. 2 is a detail view of the rib upper end connecting sleeve.

Fig. 3 is a cross sectional view of Fig. 2.

Fig. 4 is a cross sectional view of the sliding sleeve.

Fig. 5 is a face view of the rib tip member.

Fig. 6 is a cross sectional view of Fig. 5.

Fig. 7 is a view illustrating the folding of the ribs.

Fig. 8 is a reduced plan view of the inside of the cover.

Fig. 9 is a sectional view of Fig. 8 from the center to circumference showing tip 29 attached and in section.

Similar figures of reference indicate similar parts throughout the several views.

1 indicates generally the pole of the umbrella which is jointed as at 2 so that on breaking the joint the upper and lower ends 3 and 4 may be laid alongside one another. Secured to the upper end 3 of the pole is a sleeve 5 having on its upper end an integral flange 6, which flange is curved to correspond to the curvature of the cover 7 when the umbrella is opened and the cover 50 is provided at its center with a flange 8 also similarly curved the bore of which is such as to allow it to pass freely over the end of the pole to be seated on the flange 6 as shown in Figs. 1 and 3, being held firmly thereon when the umbrella is assembled by means of a flange 10 formed on the lower end of a

sleeve 11 also freely mounted on the pole and capable of being partially rotated so that the bayonet slot 12 with which it is provided will coact with a pin 13 secured 60 into the pole and by means of which slot 12 and pin 13 the flange 10 is locked in place to grip firmly between it and the flange 6 the cover flange 8.

14 indicates a sleeve adapted to be slidably mounted on the outside of sleeve 5, the lower end of which is provided with a rotatable portion 15 internally threaded to engage when rotated and being assembled a correspondingly threaded portion of the 70 sleeve 5 and thereby hold the sleeve 14 in its upmost position, as shown, abutting the underside of the flange 6, while the upper end of sleeve 14 is enlarged and slotted, as shown at 33 in Figs. 1 and 2, there being as 75 many slots, spaced equidistant from each other, as there are ribs in the complete umbrella. The enlarged slotted end of the sleeve fits when in place into a groove 41 formed in the underside of flange 6 so that 80 it is prevented from spreading under pressure.

Slidably mounted on the pole 1 is a sleeve 16 having its end portions 17 and 18 rotatable and each provided with an internal projection 19 and 20 respectively, these projections being adapted to engage threads 21 and 22 formed on the pole so that when the projection 19 is brought into contact with thread 21, or projection 20 into contact 85 with thread 22 and the respective portions 17 or 18 are rotated, as the case may be, these portions will be advanced along their respective threads and the projections 19 and 20 will be carried respectively upwardly 90 and downwardly until they slip into pockets 23 and 24 formed in the respective threads 21 and 22, when the sleeve will be temporarily locked in its upmost or downmost position, as the case may be, unlocking 100 being effected by raising the projections out of their respective pockets and rotating the portions 17 and 18 in the opposite direction. The non-rotatable portion of the sleeve is bulged outwardly and slotted, as shown at 105 34 in Figs. 1 and 4, there being as many slots as there are ribs in the umbrella.

The ribs of the umbrella, one of which is indicated by the numeral 25, are each formed in two sections and jointed at 26, 110 the joint being covered by a slidable sleeve 27 which prevents the ribs from inadvertent

5 folding at the joint but which when slid away from the joint allows the lower section of the rib to be folded toward the upper section, as indicated by the dotted lines 10 in Fig. 7. The lower end of each rib is flattened, as indicated at 28 in Fig. 7 and mounted on the flattened end is a tip member 29 the opening of which is correspondingly flattened so that when in place it will 15 not turn from its proper position. These tips on their outer sides are plate-like in formation, as indicated at 30 in Fig. 5, and provided with apertures 31 to which the umbrella cover may be stitched or otherwise connected. The upper ends of the ribs are provided with transverse members or enlargements 32 adapted to fit between the sleeve 5 and the sleeve 14 and by means of 20 which the upper ends of the ribs are retained in place after being inserted into the slots 33 of the sleeve 14.

25 The spreading of the ribs is effected in the usual manner by means of spokes, one of which is indicated by the numeral 36 in Fig. 1, their upper ends being hingedly connected to the ribs as at 37 while their lower ends are provided with transverse members or enlargements 38 similar to those on the upper ends of the ribs adapted to pass 30 through the slots 34 in the sleeve 16 to engage the inner side of the same.

35 The cover 7 of the umbrella is provided on its inside with a plurality of spaced loops 39 formed preferably by securing a tape 40 to the cover, the loops being formed by stitching the tape to the cover at the required intervals, there being as many loops as there are ribs.

40 Having thus indicated the principal parts of my invention I will now describe the manner in which it is assembled and disassembled.

45 When the umbrella is assembled the transverse ends 32 of the ribs are seated in the sleeve 14 which is tightly screwed up against the underside of flange 6 and the transverse lower ends 38 of the spokes 36 are seated in the sleeve 16, the cover 7 being secured to the pole 1 and the ribs by the 50 sleeve 11, tape loops 40 and tip members 29. To now disassemble the umbrella so that it may be folded all that is necessary is to unscrew the sleeve 15 to withdraw the upper end of the sleeve 14 away from the 55 underside of plate 6, unlock the sleeve 11 and withdraw it over the point of the umbrella, and slide the sleeves 27 to uncover the joints 26 of the ribs. The upper ends of the ribs may now be raised out of sleeve 60 14 and the lower half of each rib folded upwardly on to its upper half, the act of folding the ribs affording sufficient slackness of the cover to enable the tips 29 to be withdrawn from the ribs and to allow the 65 flange 8 of the cover to be passed over the

point of the pole so that the cover loops may be disengaged from the ribs and the entire cover withdrawn and folded away for future use. The lower sleeve 16 may then be moved upwardly to above the joint 2 and the joint broken to enable the lower end 4 of the pole to be folded alongside the upper end 3.

70 From the foregoing it will be seen that I have devised a useful umbrella which can be readily disassembled to permit its being folded into small bulk and which is characterized by the entire absence of wiring in its construction. As changes could be made, however, in the construction described, within the scope of the claims, without departing from the spirit thereof, it is intended that all matter contained in the accompanying specification and drawings be interpreted as illustrative and not in a limiting 85 sense.

What I claim as my invention is:

1. In an umbrella, a pole, a flange secured thereto having an externally threaded extension, and a sleeve adapted to detachably receive the umbrella ribs mounted on said extension having a revoluble lower part threaded internally correspondingly to the said extension, said sleeve being capable of advancement or retraction by the rotation of 95 its lower part so that its upper end abuts said flange or is removed therefrom.

2. In an umbrella, a pole, a flange secured thereto, having an annular groove in its underside and a sleeve mounted on said pole 100 capable of being advanced or retracted so that its upper end may engage in said groove to prevent its spreading or be disengaged therefrom, said sleeve being adapted to detachably receive the upper ends of the 105 umbrella ribs.

3. In an umbrella, a pole, umbrella ribs each having an enlargement on its upper end, a flange secured to the pole having an externally threaded extension, and a sleeve 110 mounted on the pole through which the upper ends of the ribs pass and with the inside of which the said enlargements engage to prevent inadvertent withdrawal therefrom of the ribs, said sleeve having a revoluble lower part threaded on to the said extension by the rotation of which the sleeve 115 may be advanced or retracted so that its upper end may abut or be removed from said flange.

4. In an umbrella, a pole, umbrella ribs each enlarged at its upper end, a sleeve secured to said pole having its upper end provided with a flange and its lower end externally threaded, a second sleeve mounted 125 on the first mentioned one having its upper end slotted with as many slots as there are ribs and each slot being adapted to receive the end of a rib directly behind the enlargement thereof, the lower end of said sleeve 130

being rotatable independently of the upper part and threaded internally correspondingly to the thread of the first mentioned sleeve.

5. In an umbrella, a pole, umbrella ribs each enlarged at its upper end, a sleeve secured to said pole having its upper end provided with a flange curved to conform to the contour of the umbrella cover when opened and having a groove in its lower face, the lower end of said sleeve being externally threaded, and a second sleeve mounted on the first mentioned one having its upper end enlarged and provided with 10 as many slots as there are ribs each of which is adapted to receive the end of a rib directly behind the enlargement thereof, the enlarged upper end of said sleeve being adapted to fit in the groove aforesaid and its 15 lower end being rotatable independently of its upper end and threaded internally corresponding to the thread of the first mentioned sleeve.

6. In an umbrella, means for detachably 25 securing the ribs thereof to the pole, comprising a sleeve having an enlarged upper end slotted with as many slots as there are ribs and having an internally threaded revolvable lower end adapted to co-act with a correspondingly threaded portion on the pole whereby said upper end may be advanced or retracted, an enlargement on each 30 rib upper end adapted to engage the inside of said sleeve when the rib is mounted in its respective slot, and a retaining flange secured to said pole against the underside of which the upper end of said sleeve may be advanced to prevent upward movement of the ribs tending to displace them out of the 35 said slots.

7. In a foldable umbrella, a jointed pole, a sleeve having an enlarged upper end slotted with as many slots as there are ribs and having an internally threaded revolvable lower end adapted to co-act with a correspondingly threaded portion on the pole whereby said upper end may be advanced or retracted, ribs jointed at substantially mid-length each provided with a movable 45 sleeve normally covering said joint and having an enlargement on its upper end, said enlargement being adapted to engage the inside of said sleeve when the rib is mounted in its respective slot, a retaining flange 50 secured to the pole against the underside of which the upper end of said sleeve may be advanced to prevent upward movement of the ribs tending to displace them out of the said slots, a cover having an apertured flange at its center adapted to be passed over said pole and seated on said retaining flange and provided with a plurality of inside loops each adapted to loop over a rib and a plurality of members around its outer edge 55 each adapted to detachably engage a rib 60 each adapted to detachably engage a rib 65

tip, and means for retaining said cover flange in place.

8. In a foldable umbrella, a jointed pole, a sleeve having an enlarged upper end slotted with as many slots as there are ribs and having an internally threaded revolvable lower end adapted to co-act with a correspondingly threaded portion on the pole whereby said upper end may be advanced or retracted, ribs jointed at substantially mid-length each provided with a movable sleeve normally covering said joint and having an enlargement on its upper end, said enlargement being adapted to engage the inside of said sleeve when the rib is mounted in its respective slot, a retaining flange secured to the pole against the underside of which the upper end of said sleeve may be advanced to prevent upward movement of the ribs tending to displace them out of the said slot, a cover having an apertured flange at its center adapted to be passed over said pole and seated on said retaining flange and provided with a plurality of inside loops each adapted to loop over a rib and a plurality of members around its outer edge each adapted to detachably engage a rib tip, and a rotatable sleeve mounted on said pole adapted to bear on the upper face of said cover flange provided with a bayonet slot 95 co-acting with a locking pin carried by said pole.

9. In a foldable umbrella, a jointed pole, a sleeve mounted thereon having an enlarged upper end slotted with as many slots as there are ribs and having an internally threaded revolvable lower end adapted to co-act with a correspondingly threaded portion on the pole whereby said upper end may be advanced or retracted, ribs jointed at substantially midlength each provided with a movable sleeve normally covering said joint and having an enlarged upper end and a flattened tip, said enlargement being adapted to engage the inside of the said sleeve when the rib is mounted in its respective slot, a retaining flange grooved on its underside secured to the pole against which the upper end of said sleeve may be advanced to prevent displacement from said slots of said ribs and to engage in said groove, a cover having an apertured flange at its center adapted to be passed over said pole and seated on said retaining flange and provided with a plurality of inside loops each adapted to loop over a rib and a plurality of members around its outer edge adapted to detachably engage the flattened tips of the said ribs, and means for retaining said cover flange in place.

10. In a foldable umbrella, a jointed pole, an upper sleeve having an enlarged upper end slotted with as many slots as there are ribs and having an internally threaded revolvable lower end adapted to co-act with a cor-

respondingly threaded portion on the pole whereby said upper end may be advanced or retracted, an enlargement on each rib upper end adapted to engage the inside of said sleeve when the rib is mounted in its respective slot, a retaining flange secured to said pole against the underside of which the upper end of said sleeve may be advanced, a sliding sleeve mounted on the pole having its upper and lower portions revoluble and provided with internal projections and its mid-portion slotted with as many slots as there are ribs, said projections being adapted to co-act respectively with upper and lower threads on the pole, and spokes extending between said sleeve and said ribs, the lower ends of the spokes being engaged in the slots of the said sleeve.

11. In a foldable umbrella, a jointed pole, an upper sleeve having an enlarged upper end slotted with as many slots as there are ribs and having an internally threaded revoluble lower end adapted to co-act with a correspondingly threaded portion on the pole whereby said upper end may be advanced or retracted, an enlargement on each rib upper end adapted to engage the inside of said sleeve when the rib is mounted in its respective slot, a retaining flange secured to said pole against the underside of which the upper end of said sleeve may be advanced, a sliding sleeve mounted on the pole having its upper and lower portions revoluble and provided with internal projections and its mid-portion slotted with as many slots as there are ribs, said projections being adapted to co-act respectively with upper and lower threads on the pole having pockets with which said projections engage at a predetermined point of their travel, and spokes extending between said sleeve and said ribs the lower ends of the spokes being engaged in the slots of the said sleeve.

Copies of this patent may be obtained for five cents each, by addressing the "Commissioner of Patents, Washington, D. C."

12. In an umbrella, a pole, and means mounted thereon for opening and closing the umbrella, said means comprising a sliding sleeve mounted on the pole having its upper and lower portions revoluble and provided with integral projections and its mid portion slotted with as many slots as there are umbrella ribs, and threads on the pole with which the projections of the said upper and lower portions coöperate to limit the opening and closing movements of the sleeve, and spokes the upper ends of which are hingedly connected to the umbrella ribs, their lower ends being seated in the slots of said sleeve.

13. In an umbrella, a pole, and means mounted thereon for opening and closing the umbrella, said means comprising a sliding sleeve mounted on the pole having its upper and lower portions revoluble and provided with internal projections and its mid portion slotted with as many slots as there are umbrella ribs, threads on said pole with which the projections of the said upper and lower portions coöperate to limit the opening and closing movements of the sleeve, each said thread having a pocket with which the respective internal projections engage to prevent inadvertent rotation of the respective revoluble portions, and spokes the upper ends of which are hingedly connected to the umbrella ribs, their lower ends being seated in the slots of said sleeve.

14. In an umbrella, a pole, umbrella ribs detachably secured to said pole and provided with flattened tips, a cover, and means carried thereby for detachably securing its outer edge to the said tips, said means comprising sockets flattened correspondingly to the tips and adapted for slidably engagement thereon.

Dated at Vancouver, B. C., this 3rd day of July, 1918.

PERCIVAL FAULKNER KING.
